CLAIM

The ornamental design for a bumper headlight assembly for golf car, as shown and described.

DESCRIPTION

FIG. 1 is a front, left and top perspective view of a bumper headlight assembly for golf car showing my new design;

FIG. 2 is a rear, right and bottom perspective view thereof.

FIG. 3 is a front elevational view thereof.

FIG. 4 is a back elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken line portion of the drawings is included to show unclaimed subject matter only and forms no part of the claimed design.
